(57) **CLAIM**

The ornamental design for a wall map, as shown and described.

DESCRIPTION

1. Wall map

1.1 : Front

1.2 : Enlarged perspective view

1.3 : Enlarged front view

1.4 : Enlarged front view

1.5 : Enlarged front view

1.6 : Enlarged front view

1.7 : Enlarged front view

1.8 : Enlarged front view

1.9 : Enlarged front view

1.10 : Enlarged front view

1.11 : Front partial view

1.12 : Front partial view

1.13 : Front partial view

1.14 : Front partial view

Design is a detailed three-dimensional wall ornament shaped as the world map; the design comprises portions that are shaped as; geographical objects, for example continents, islands, oceans, that are placed in such a way as to accurately copy the actual geographical location of the respective objects and the appearance of the coastline and reproduce in detail the shape and dimensional relationship of geographical objects, decorative portions shaped as means of transport, namely planes and yachts, and a compass; are combined together into a single composition.

1 Claim, 14 Drawing Sheets
